(57) **CLAIM**

The ornamental design for a wine bubbler device, as shown and described.

DESCRIPTION

FIG. 1 is a perspective view of a wine bubbler device embodying our new design;

FIG. 2 is another perspective view of the structure of FIG. 1 from a different perspective view in relation to FIG. 1;

FIG. 3 is a front elevation view of the structure of FIG. 1;

FIG. 4 is a rear elevation view of the structure of FIG. 1;

FIG. 5 is a left side elevation view of the structure of FIG. 1;

FIG. 6 is a right side elevation view of the structure of FIG. 1;

FIG. 7 is a top plan view of the structure of FIG. 1;

FIG. 8 is a bottom plan view of the structure of FIG. 1;

FIG. 9 is a perspective view of another embodiment of a wine bubbler device embodying our new design;

FIG. 10 is another perspective view of the structure of FIG. 9 from a different perspective view in relation to FIG. 9;

FIG. 11 is a front elevation view of the structure of FIG. 9;

FIG. 12 is a rear elevation view of the structure of FIG. 9;

FIG. 13 is a left side elevation view of the structure of FIG. 9;

FIG. 14 is a right side elevation view of the structure of FIG. 9;

FIG. 15 is a top plan view of the structure of FIG. 9; and,

FIG. 16 is a bottom plan view of the structure of FIG. 9. The broken lines depict environmental subject matter, are for illustration only and form no part of the claimed design.

1 Claim, 8 Drawing Sheets
